FUSE HOLDER

Orie E. Pine, Galesburg, Ill., assignor to Midwest Manufacturing Corporation, Galesburg, Ill., a corporation of Illinois

Application January 27, 1955, Serial No. 484,411

3 Claims. (Cl. 200—133)

This invention relates to improvements in fuses for the protection of electrical circuits and more particularly to a fuse holder of the type where the fuses are replaceable.

An object of the invention is to provide a fuse holder where the fuse may be replaced without the use of tools.

Another object of the invention is to provide a fuse holder where the fuse being renewed may be inserted without any danger of contact with an electrical circuit.

Another object of the invention is to provide a fuse holder which is simple, economical to manufacture and easy to service.

Another object of the invention is to provide a fuse holder and a receptacle therefor where connections to the wires in the electrical circuit may be made without the use of tools.

Another object of the invention is to provide a fuse holder which is compact.

In the drawings:

Fig. 1 is a vertical medial sectional view of my invention;

Fig. 2 is a view with the cover removed and looking into the housing of the holder of my invention;

Fig. 3 is a section taken on the line 3—3 of Fig. 2;

Fig. 4 is an end view of the housing;

Fig. 5 is an elevational view of the fuse holder removed from the housing;

Fig. 6 is a plan view of a fuse as used in a fuse holder;

Fig. 7 is a plan view of the fuse holder with a fuse in position prior to assembly;

Fig. 8 is an elevational view of a contact member; and

Fig. 9 is a plan view of the outer surface of the holder.

Briefly, my invention comprises a receptacle having contact making strips at its ends adapted to make contact with wire conductors and a fuse holder and cover, which carries the fuse and brings it into contact with the contact strips when it is forced into position.

More particularly the housing comprises an open ended box of rectangular formation having end walls 11 and side walls 12 which extend at right angles from a base 13 that may be integral with the walls. Centrally of the base there is provided a rectangular boss 15 having a circular central opening 16 for receiving the head of a screw 17, which may seat in the bottom of the opening 16 and extend through a hole 18 and be threaded into a support 19. If desired, positioning lugs 20 may be provided for engagement in suitable recesses in the support.

The end walls 11 each have secured thereto a contact member which, as is best shown in Fig. 8, may comprise a body 21 having a central aperture 22 enabling it to be secured to the end walls by rivets 23. Extending from the aperture 22 to the end of the member are a pair of arms or legs 25 which are separated by a slit 26 that extends into the aperture. Each of the arms is provided with a V-shaped notch 27 in its end. The tips of the arms may bend inward slightly, as can be seen in Fig. 1. Spaced from the end of the contact member there is formed a rib 30 which extends transversely of the mem-

2

ber and which is preferably made by deforming the member at this point.

The end walls 11 are provided with pairs of openings 33 which are opposite to the apex of the V notches in the arms 25 of the contact member. The contact member is made of a flexible metallic material, such as copper or beryllium copper, having suitable inherent resiliency. In operation, insulated conductors 35 are inserted through the openings 33 and when so inserted the contact strip flexes inward away from the wall, as shown by the dotted lines in Fig. 1, to such an extent that the walls defining the V notch 27 may engage with the periphery of the insulation. Then, after the notch is in engagement with the periphery of the conductor it is pulled backward outwardly of the housing to the position as shown by the full lines, in Fig. 1, at which time the edges of the member defining the notch 27 penetrate the insulation and make good contact with the wire conductor itself. Thus a connection can be quickly made by simply shoving the end of the conductor through one of the holes 33 as far as it will go until it hits the center abutment 15 and then pulling it outward a slight distance.

If desired, ventilating holes 36 may be provided in the wall of the housing near the base.

The fuse holder comprises a cap portion 40 from which there extends upwardly a pair of rectangular bosses 41 connected by a shallow neck 42. The periphery of the bosses 41 and the neck 42 are of rectangular formation with the sides providing a close fit with the side walls 12 of the housing. Each of the bosses 41 is provided with a transversely extending groove 43 spaced from the cap 40 and extending in a horizontal direction, as viewed in Fig. 5.

Each of the bosses is also provided with an upper portion 44 slightly shorter in length than the supporting bosses 41 and through which is formed a longitudinally extending slot 45 extending across the boss for approximately two-thirds of its distance, as can best be seen in Fig. 7. The two slots are in horizontal alignment with each other and are of a width approximately that of the thickness of the fuse element to be used, but slightly larger, to permit easy insertion of the fuse element and of a depth considerably greater than the width of the fuse element.

The fuse element, as shown in Fig. 6, consists of a center fusible portion 47 flanked by a pair of enlargements 48 which are connected to enlarged ends 49 by short necks 50. It will be appreciated that the width of the center 47 for a given thickness of fuse element determines the current carrying capacity.

The outer face of the cap is provided with undercut portions 55 extending into the cap from opposite sides and providing a strip 56 in the center of the cap which serves as a handle which may be engaged for removing the same.

The fuse element, as can best be seen in Fig. 7, is inserted in the slots 45. In this position the enlarged portions 48 are disposed in the slots and the fusible portion 47 is suspended in mid-air between the bosses 41. The necks 50, which obviously must be larger than the blowable portion 47 in order to insure that it will carry the maximum amount of current intended, are disposed approximately opposite the ends of the bosses 41 and provide a weakened portion which enables the enlarged ends 49 to be bent downward alongside the ends of the bosses 41, at which time they extend over the grooves 43. In other words, the fuse element is shoved into the slots 45 and bent down at the ends over the grooves. It should be noted that this is the only act necessary for the installation of the fuse element and that it is performed completely away from the contacts so that no danger of shock will be encountered. When the fuse

element is installed in the holder in the manner described, the holder is then forced into position in the main housing. This carries the ends 49 over the ribs 30 on the contacts, and, when in position, the ribs 30 depress the portions of the part 49 into the grooves 43 on the bosses. This performs the dual function of holding the cap and its fuse in place and making a good electrical contact with the fuse and the end contact plates.

When the fuse breaks down it is merely necessary to grasp the handle 56 and pull the cap out of the housing, after which the burned fuse parts may be removed and a new one installed. Because of the depth of the slot 45 it will be appreciated that wider fuses may be used, or, when not available, two narrow fuses may be used juxtaposed to each other.

It will therefore be apparent that I have provided a fuse assembly that may be quickly connected into a circuit without any special tools and where the fuse may be renewed quickly, easily and economically.

Having thus described my invention it will be appreciated that the structure shown in the drawings has been selected largely for the purpose of illustration, and that various changes in the parts may be made without departing from the spirit or scope of the invention as is defined in the appended claims.

I claim:

1. A fuse holder unit comprising a housing having opposite end walls, contact strips secured to said end walls being provided with transverse ribs and resilient arms having V-shaped notches, said housing being formed with apertures opposite said notches through which an insulated wire may be passed to move said arms away from the housing and engage the wire in said notches, a fuse holder releasably secured within said housing comprising a cap member having fuse holding means arranged to extend into said housing, said means being formed with transversely extending grooves disposed opposite to the ribs on said contact strips, a fuse carried by said fuse holding means and having portions disposed over said grooves and resiliently engaged by said transverse ribs on said contact strips whereby said portions are deformed into said grooves.

2. A fuse holder unit comprising a rectangular housing having vertically extending side and end walls and an open face, contact strips secured to the end walls and arranged to be engaged with a conductor, said strips extending from near the bottom of the housing to the open face thereof and being provided with transverse ribs

spaced from the open face of the housing, a fuse holder releasably secured within said housing comprising a cap adapted to overlie the edges of the housing defining said open face and formed with a pair of spaced bosses thereon arranged to extend within the housing, said bosses being provided with longitudinally aligned slots for the reception of a fuse therein and being formed with transversely extending grooves disposed opposite to the ribs on said contact strip, fuse means disposed in said longitudinally aligned slots extending toward the ends thereof and over said grooves and arranged to be deformed into the grooves by contact with said ribs on said contact strips, said fuse having a central blowable portion disposed between the bosses and enlarged portions disposed in the bosses and an easily bendable portion spaced from the rib contact ends thereof and disposed opposite to the corners of the bosses.

3. An article of the class described including a wall having openings therein, a flexible contact member secured to the wall spaced from said openings, said member being formed with flexible legs each having a V-shaped notch in the end thereof with the material defining the notch partially overlying one of said openings, said member being arranged to be pushed away from the openings by a conductor a sufficient distance for the conductor to engage in said notch and the edges of said notch being arranged to penetrate the wall of the conductor and make contact with the wire when the conductor is pulled outward of the opening, said member being provided with a rib spaced from its connection to the wall and opposite from said legs and arranged for engagement with a fuse.
